CLAIM

The ornamental design for an automobile taillight, as shown and described.

DESCRIPTION

1. Automobile taillight

1.1 is a left side elevation view of an automobile taillight showing our new design;

1.2 is a right side elevation view thereof;

1.3 is a rear elevation view thereof;

1.4 is a top plan view thereof;

1.5 is a top, front, and right side perspective view thereof;

1.6 is a front elevation view thereof; and

1.7 is a bottom plan view thereof.
